IGNITING SYSTEM FOR SMUDGE POTS

Robert H. Dart, Sacramento, Calif.

Application August 22, 1932, Serial No. 629,838

10 Claims. (Cl. 44—36)

This invention relates to improvements in means for igniting the contents of smudge pots such as are used in orchards to minimize the harmful effects of frost.

At present these smudge pots must be individually lit, which takes a number of men to cover all the ground within a reasonable length of time and who must be kept on hand by the owner for the full period during which a frost may be expected. This also necessitates the owner or his foreman having to make nightly vigils while keeping track of the temperature in order that the pots may be lighted when the temperature has dropped to the low point necessary to warrant smudging operations. This present method of operation obviously entails considerable labor cost which in the aggregate totals up to a considerable amount.

The principal object of my invention is to avoid and eliminate the above named inconvenient, costly and inefficient method by providing an electrically actuated system by means of which the contents of all the smudge pots may be ignited simultaneously; the electrical apparatus being preferably actuated by a suitably positioned thermostat, or by a single hand switch in the operating house. The smudge pots after once having been used must of course be refilled, and the ignition starting members replaced. This latter operation however may be done in conjunction with the refilling of the pots and may consume but little additional time.

The operator thus need only fill the pots and replace the ignition members and may then leave the premises without further care knowing that should the necessity arise the pots will be ignited at the proper time.

A further object is to provide an electric igniting apparatus of such a nature that low tension and cheap wiring may be used, and such wiring may be of a portable nature, resting on the ground between the pots. The use of my improved system thus does not entail any permanent insulation in the orchard and the installing and operating costs are very low.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference 55 indicate corresponding parts in the several views:

Fig. 1 is a side view of an igniting unit partly broken away and in section shown as installed and in connection with a smudge pot.

Fig. 2 is a perspective view of an igniting cartridge as mounted in its hanger the latter being detached from its support.

Fig. 3 is a diagram of a circuit for the pot cartridge igniter and a preferred form of switch arrangement therein.

Referring now more particularly to the characters of reference on the drawing, the numeral 1 denotes the side wall of a smudge pot of any standard character adapted to contain a supply of the usual oil 2 to be ignited. Provided for detachable engagement with the rim of the pot is a 70 clamping bracket or hanger 3 on which is mounted an insulation block 4 which overhangs the pot.

A small low voltage electric ignition element 5 such as is used in various cigarette and cigar lighters is mounted on and depends from the under face of the block inwardly of the bracket. Said element is adapted to ignite the adjacent end of an inflammable cartridge 6 which depends into the pot from under the element. This cartridge may be made of any suitable material 80 such as a cellulose product, the waste matter from paper pulp mills, sawdust, and like products. These if necessary may be impregnated with or dipped in a substance of a more readily inflammable nature or which aids in combustion, 85 such as paraffine and other hydro-carbon products. The use of materials of the above general character will not only absorb a certain quantity of what is now considered waste but enables the cartridges to be molded into any desired shape. 90 The cartridges must be of such a material as will not sink to the bottom of the oil and are preferably of a relatively light density at the top so that they will catch on fire and burn quickly at that end; and of relatively heavy density toward 95 the bottom so that when once burning they will last for some little time.

The cartridge is arranged to be supported from adjacent its upper end from the block 4 and in close relation to and under the element 5, and so 100 that it will drop onto the oil when the upper portion of the cartridge has been burned away. This may be done in various ways. In the present case I show the cartridge as being formed with a pair of opposed lugs 7 toward the top, of the same 105 material as the cartridge so that they will also burn. These lugs are adapted to rest on spaced signal rings 8 which surround the cartridge toward its upper end and which are supported from the block 4 by elements 9 depending therefrom. 110

The spacing between the rings is sufficient to permit the insertion of the lugs therebetween so that the cartridge may be placed in position by raising it with the lugs projecting upwardly between said rings, and then turning the cartridge so that the lugs rest on the rings.

When the element 5 is energized therefore the cartridge being in close relationship therewith will be ignited, and after its upper portion including the supporting lugs has burned away it will drop of its own weight onto the oil while continuing to burn. The size and density of the then remaining portion of the cartridge is such that it will burn for some time after dropping, as for instance two or three minutes, insuring the ignition of the oil with which it is in contact even when the oil is in a cold condition, as will naturally be the case. To promote the ignition and subsequent burning of the cartridge it may be provided with a longitudinal draft opening 10 therethrough and lateral openings 11 toward the bottom as well if desired.

To prevent the conductors to the igniting element from being damaged by the heat or flame from the burning oil the leads from said element extend through the block 4 to binding posts 12 on its outer edge, which is outwardly of the pot, and to which the line wiring is detachably connected by clips 13 as indicated in Fig. 1.

30 The wiring 14 for each row or series of pots is laid along the ground adjacent the row, being connected in parallel to the various elements 5. These wires are connected to the main line wires 15 in which a thermostatically controlled switch 16 may be interposed at such a location as to be actuated by a temperature the same as that in the orchard itself.

40 A hand switch 17 may also be interposed in the line so that the circuit may be broken after it has been closed for some time, or an automatic time actuated circuit breaking device may be provided for the purpose. I also preferably connect a bypass line 18 to the main line around the thermostat switch, with a hand switch 19 therein so that the circuit may be closed and opened if desired independent of the action of the thermostat switch.

50 From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

60 1. A device for igniting the contents of a smudge pot including an inflammable body, means incorporated in part with said body only adjacent its upper end for holding the same in overhanging relation to said contents of the pot, and means to ignite the body at its upper end.

70 2. A device for igniting the contents of a smudge pot including an inflammable body, means for igniting the body at its upper end, and means relatively unaffected by heat supporting the body toward its upper end in suspended relation to the contents of the pot whereby when said

upper end portion has burned away, the burning body will drop of itself onto said contents.

3. The method of igniting the contents of a smudge pot consisting in placing an inflammable body over the pot, suspending the body above the contents of the pot in such a manner that when burned away a certain amount at its upper end the body will drop of itself into the pot, and igniting the body at its upper end.

4. A device for igniting the contents of a smudge pot comprising a block, means to support the block on the pot in overhanging relation thereto, a downwardly facing electric ignition element mounted on the under side of the block, an inflammable body depending from under and in close relation with the element, and means detachably supporting the body from the block so that when the upper end portion of the body has burned away, it will drop of itself into the pot.

5. A device for igniting the contents of a smudge pot comprising a block, means to support the block on the pot in overhanging relation thereto, a downwardly facing electric ignition element mounted on the under side of the block, an inflammable body depending from under and in close relation with the element, lugs formed of the body material projecting outwardly from the body toward its upper end, and members suspended from the block on which said lugs detachably rest.

6. A device for igniting the contents of a smudge pot including a floatable combustible body, means normally supporting the body adjacent its upper end in overhanging relation to the pot, and means to ignite the upper portion of the body whereby after the supported portion of the body has burned away said body will drop into the pot and will continue burning while floating on the surface of the contents thereof.

7. A device for igniting the contents of a smudge pot including a combustible body, means normally supporting the body adjacent its upper end in overhanging relation to the pot, and means to ignite the upper portion of the body whereby after the supported portion of the body has burned away said body will drop into the pot, the body being of a floatable character and having a relatively lower density at its upper than toward its lower end.

8. A structure as in claim 1, in which the body is formed with a draft passage therethrough.

9. A device for igniting the contents of a smudge pot including a unitary combustible body capable of burning for some minutes, means to ignite the body at one end, and means supporting the body in overhanging relation to the pot so that said end is uppermost and so that said body will be free to drop of itself into the pot after the upper end portion only of the body has burned away.

10. A device for igniting the contents of a smudge pot including a floatable combustible body capable of burning for some time, means to ignite the body, and means supporting the body in overhanging relation to the pot and so that the body is free to drop of itself into the pot after only a relatively small portion of the body has burned away whereby said body will continue to burn while floating in the contents of the pot.

ROBERT H. DART.
